(57) **CLAIM**

The ornamental design for an earth drill, as shown and described.

DESCRIPTION

FIG. 1 is a perspective view of an earth drill showing my new design;

FIG. 2 is left side elevational view thereof;

FIG. 3 is a right side elevational view thereof;

FIG. 4 is a top plan view thereof;

FIG. 5 is a bottom plan view thereof;

FIG. 6 is a front elevational view thereof; and,

FIG. 7 is rear elevational view thereof.

The vehicle depicted in broken lines in FIG. 1 is environmental structure forming no part of the design.
